(57) **CLAIM**

The ornamental design for a golf training shoe, as shown and described.

DESCRIPTION

FIG. 1 is a front view of a golf training shoe showing a left shoe and a right shoe in juxtaposition as a set, wherein the broken lines represent the shoe structure as part of the environment;

FIG. 2 is a rear view thereof; and,

FIG. 3 is a top view thereof.

The broken lines in the drawings, showing the remainder of the shoe, illustrate the environment of the article and form no part of the claimed design.
